CLETUS CLINTON VAN VOORHIS, OF EAST ORANGE, NEW JERSEY, ASSIGNOR TO WEST-
INGHOUSE LAMP COMPANY, A CORPORATION OF PENNSYLVANIA.

MANUFACTURE OF ELECTRIC LAMPS AND THE LIKE.

Application filed June 21, 1922. Serial No. 569,861.

This invention relates to the manufacture of electrical devices comprising evacuated or gas-filled envelopes and more particularly to the introduction of unstable 5 volatile substances into electric lamps and the like.

An object of my invention is the provision of a method of handling unstable substances whereby they may be used in a substantially 10 pure condition, uncombined with oxygen, water vapor and the like.

Another object of my invention is the introduction of chemically active substances or "getters" into envelopes of electric lamps, 15 radio-tubes, photo-electric cells and the like in minute quantities and in substantially pure condition.

A further object of my invention is the provision of a method for supplying a small 20 quantity of a pure metal, such as one of the alkali metals, uncombined with oxygen, water vapor or other substance having an affinity therefor, to an electric glow lamp or the like.

Other objects and advantages of the 25 invention will be apparent as the description proceeds.

In the manufacture of electric devices, such as rare-gas glow lamps, vacuum or 30 gas-filled incandescent lamps, vapor lamps, photo-electric cells and the like, it is desirable, in many cases, to introduce a small quantity of an active substance in the pure state, such as a volatile metal. In glow lamps, for example, it is desirable to introduce an alkali metal to lower the starting and operating voltage thereof. On account of the rapid action of oxygen and moisture on many of such substances, they must be kept from contact with the air to prevent the combination with oxygen, moisture and other substances having an affinity therefor.

Some substances, such as potassium and phosphorus, will, in some cases, ignite spontaneously when exposed to the action of water and air, respectively. Consequently, active substances of the aforementioned character cannot be introduced into electric lamps and the like and remain in a pure 50 uncombined condition unless the air has previously been evacuated therefrom.

The method commonly used is to construct the bulb or the like into which the volatile metal or getter is to be introduced with a side tube containing some of such

substance. The metal or getter is then volatilized into the bulb after which the side tube is sealed off of the bulb. According to the previously described method, the side tube is not especially adapted for protecting the substance to be introduced from the action of the atmosphere and is used for supplying only one bulb with a volatile metal or the like, and the process is, therefore, expensive and slow.

In accordance with my invention, I may use the following method for introducing volatile substances into electric lamps and the like. Although I will describe my method with reference to the introduction 70 of volatile metals, it is to be understood that other volatile substances, such as phosphorus, for instance, may be introduced in the same manner, if desired.

A purified volatile metal is first put into 75 specially constructed glass tubes by any known method, that is, the metal may be melted in vacuo or in an inert atmosphere and poured into a tube constructed of a glass which is not attacked by the melted metal, such as pyrex or lime glass. The tubes are so constructed that, even when open at one end, the volatile metal therein is protected substantially from atmospheric action. One of these tubes containing metal 80 may be connected to a system for exhausting or gas-charging a lamp or a series of lamps. The lamp may be exhausted and some of the metal in the tube be then melted and vaporized until the desired amount is introduced into the exhaust system where it may be flushed into the lamp by a flow of inert gas or allowed to flow into the lamp by its own pressure.

My invention will better be understood 85 by reference to the accompanying drawing in which,

Fig. 1 is a side elevation of a tube for holding a volatile metal or other substance;

Fig. 2 is a side elevation illustrating a 100 rare-gas glow lamp and one of such tubes connected to a system for exhaustion and gas charging;

Fig. 3 is a side elevation showing a modification of the arrangement shown in Fig. 105 2; and,

Fig. 4 is a plan view of the arrangement shown in Fig. 3.

In practicing my invention, the tube or container 1 (Fig. 1), comprising an en-

larged portion or reservoir 2, a central contracted portion 3, and an end portion 4, may be filled with a volatile metal or other substance 5 which preferably completely 5 fills the reservoir 2 and extends part way through the contracted portion 3. The end portion 4 may be sealed by tipping off at 6 so that the volatile metal 5 may be kept for any length of time until it is desired to use 10 the same. The middle section 3 of the tube is narrow, the inside diameter being preferably about $\frac{1}{8}$ inch, though it may be larger or smaller. The length of this narrow section may vary from approximately 15 $\frac{1}{4}$ inch to an indefinite length, being preferably about 2 inches.

The enlarged portion 2 preferably has a diameter larger than that of the middle section 3, so as to hold the required amount of 20 metal without being unduly long. The end portion 4 may have a diameter equal to or greater than the middle portion 3. The tube may be bent at the narrow part 3, so that it may be sealed to an exhaust system, 25 with the end portion 4 substantially horizontal and the reservoir 2 extending to a higher elevation than the narrow part 3 so that, when the metal is melted, it will flow by gravity into the narrow part 3 and thus 30 expose only a small surface to be acted on by air or moisture. The tube 1 is preferably constructed of transparent material, such as pyrex or lime glass, which is not appreciably attacked by melted alkali metals or the like. 35 In order to use the metal 5 in the tube 1, part of the end portion 4 is cut off, and the tube 1 is sealed to a pipe or tube 7 of an exhaust system, (Fig. 2) at a point 8 preferably near to the lamp 9 which is to be exhausted. The exhaust system may comprise 40 a connection to a vacuum pump or the like (not shown) and a source of inert gas, (not shown) if it is desired to produce gas-filled lamps. The lamp 9 may be exhausted 45 through contraction 11, and a suitable amount of said metal distilled from the tube 1 by means of heat applied in any desired manner. While the portion of the tube from the metal in the reservoir to the 50 connection to the exhaust pipe is kept hot, the exhaust pipe 7 may be warmed up in the region from the contraction 11 to some distance beyond the connection 8 between the tube 1 and the exhaust pipe. A current of 55 a gas, such as argon, inert to the volatile metal, may then be allowed to slowly stream through the contraction 11, thus sweeping the desired amount of volatile metal vapor into the lamp 9.

60 Some of the volatile metal may be distilled directly from the tube 1 into lamp 9, through the exhaust pipe 7, without using any inert gas to sweep or flush the metal vapor in, but the inert gas streaming 65 through the tube 7 makes it possible to in-

70 produce the desired amount of volatile metal into the lamp in a much easier and quicker manner than without its use. The metal will condense and deposit on the inside of the lamp 9, and the gas may then be pumped back into a reservoir by means of any suitable pump.

In case an inert filling is to be put into the lamp 9, as in the manufacture of rare-gas glow lamps, the volatile metal may be 75 introduced at the time the filling is made, thus obviating the necessity of pumping out the gas used to sweep in the volatile metal vapor. This procedure has the added advantage, in the case of some metal vapors, 80 such as those of the alkali metals, in that such metals have a purifying action on gases which are inert to them.

If a considerable quantity of the volatile metal is to be introduced, the tube 1 may be 85 inclined so that the metal may be melted and caused to flow down through exhaust tube 7 and into lamp 9.

90 After the lamp 9 has been suitably treated and tipped off at the contraction 11 and while a new lamp is being connected to exhaust tube 7, air will come into contact with the metal in tube 1. However, as section 3 of tube 1 is narrow and normally closed by a 95 column of metal, the amount of metal surface exposed and oxidized will be very small, because of the slow diffusion through such a narrow tube of a fresh supply of oxygen or moisture to this surface and because the thin film of oxide first formed serves as a 100 protective coating against further action.

105 Such oxide, in some cases, will not be volatile enough to distill out of tube 1, when metal vapor is distilled therethrough. In other cases, it may easily be driven far up into exhaust tube 7 with a very small amount of metal where it will not interfere any further with the process, this being best accomplished as the exhaustion of the bulb is nearing completion. By the method just described, the volatile metal or other active substance may be introduced into a large 110 number of lamps, bulbs or the like, from one tube or container, without requiring the sealing of a container to each bulb and subsequent sealing-off of the same.

115 Figs. 3 and 4 show a modified arrangement of apparatus suitable for introducing a volatile metal to a number of lamps at once, instead of into only one lamp at a time, as previously described. The apparatus for practicing this method for a plurality of lamps or other vessels may comprise a glass manifold 12 composed of a 120 multiplicity of tubes 13 going out of a common central chamber 14. From this chamber 14, which is kept as small as possible, one tube 15 may extend vertically upward for attachment to the evacuating or gas-charging tube 7, and another tube, such as 125

1, may extend vertically downward and contain metal or other substance to be volatilized into the lamps or bulbs. The lamps or other envelopes 9, to be treated according to my invention, are connected through contraction tubes 11, in any suitable manner, to the outstanding tubes 13 of the glass manifold.

It will be readily understood that, upon 10 heating the metal in tube 1, any desired amount thereof may be introduced into the lamps in a manner similar to that previously described with reference to Fig. 2.

Although I have described my invention 15 with respect to volatile metals, it is to be understood that any other volatile substance suitable for introducing into a lamp bulb or the like may be used within the spirit and scope of my invention which is limited only 20 in accordance with the following claims.

What is claimed is:

1. The method of causing a small amount of a volatile substance to pass into a vessel connected to an exhaust system and a source 25 of a relatively inert gas, comprising connecting to the exhaust system a tube of said substance, vaporizing a portion thereof and sweeping the desired amount of the same into the vessel by a stream of the inert gas.

2. The method of introducing a volatile substance into a vessel, comprising connecting said vessel to an exhaust system, connecting a container of said substance comprising a tubular restricted portion to said 30 exhaust system by said restricted portion, exhausting said vessel and heating said restricted portion until the required amount of said volatile substance is vaporized and passes into said vessel.

3. The method of introducing a small amount of a volatile substance into a vessel, comprising connecting said vessel and a tube of said substance to means for exhausting said vessel, exhausting said vessel and heating said tube until the desired amount of said substance is vaporized and sweeping a requisite amount of said vaporized substance into said vessel by a stream of inert gas.

4. The method of introducing a volatile 45 metal into a glow lamp or the like, comprising connecting said lamp to means for exhausting the same, connecting a container of said volatile metal with a restricted portion normally closed thereby to said means

for exhausting, evacuating the lamp and 55 heating the restricted portion until the desired amount of metal is vaporized and passes into said lamp.

5. The method of introducing a volatile metal into a lamp, comprising connecting 60 said lamp and a tube of said volatile metal to a vacuum pump and a source of inert gas, exhausting said lamp, heating said tube until the requisite amount of volatile metal is 65 vaporized and sweeping the desired amount of volatile metal into said lamp by a stream of inert gas.

6. The method of introducing a volatile readily-oxidizable metal into a vessel, comprising connecting said vessel to an exhaust 70 system, preparing a container holding some of said metal and comprising a reservoir and a tubular restricted portion extending therefrom, connecting said tubular restricted portion to the same exhaust system near the 75 connection of the vessel thereto, applying heat to said restricted portion to vaporize the requisite amount of volatile metal and causing it to pass into said vessel.

7. The method of introducing a readily-oxidizable volatile metal into a vessel, comprising connecting said vessel to a system for exhausting the same, attaching to said system a reservoir containing a quantity of said volatile metal, by means of a tubular 85 restricted portion, exhausting said vessel and heating said volatile metal in said restricted portion until the desired amount thereof is vaporized and passes into said vessel.

8. The method of introducing a small amount of readily-oxidizable volatile metal into a vessel comprising connecting said vessel to a system for exhausting the same, attaching a reservoir filled with a quantity of 95 volatile metal to said system for exhausting by means of a restricted tube below the level of the volatile metal, exhausting said vessel and heating said volatile metal in said tube until the requisite amount thereof is vaporized and passes into said exhaust system and sweeping said metal into said evacuated vessel by means of a stream of inert gas.

In testimony whereof, I have hereunto subscribed my name this 20th day of June, 105 1922.

CLETUS CLINTON VAN VOORHIS.
